UNITED STATES PATENT OFFICE.

FRIDOLIN SCHIMMEL, OF FARIBAULT, MINNESOTA.

DESK-TABLE.

1,292,089.

Specification of Letters Patent. Patented Jan. 21, 1919.

Application filed September 22, 1917. Serial No. 192,787.

To all whom it may concern:

Be it known that I, FRIDOLIN SCHIMMEL, a citizen of the United States, residing at Faribault, in the county of Rice and State 5 of Minnesota, have invented certain new and useful Improvements in Desk-Tables; and I do hereby declare the following to be a full, clear, and exact description of the invention, such as will enable others skilled 10 in the art to which it appertains to make and use the same.

My invention has for its object to provide a so-called desk table which is in the nature of a portable device or attachment adapted 15 to be applied to a table, or, in fact, to a flat support, and, when applied, to afford the conveniences of a desk having various compartments, such as drawers and open receptacles.

20 To the above ends, generally stated, the invention consists of the novel construction and combination of parts hereinafter described and defined in the claim.

In the accompanying drawings which 25 illustrate the invention, like characters indicate like parts throughout the several views.

Referring to the drawings,

Figure 1 is a front elevation showing the 30 so-called desk table applied to an ordinary flat top table, such as a library table or card table, the wings of the said desk table being opened out;

Fig. 2 is a plan view of the parts shown in Fig. 1; and

35 Fig. 3 is a plan view of the desk table or attachment showing the wings thereof folded and some parts being broken away.

The ordinary flat top table is indicated, as an entirety, by the numeral 4. The desk 40 table or attachment has a flat rectangular base 5 and is provided on its rear half portion with a raised flat top superstructure 6, in which are drawers 7 and an open central space 8. To the front edges of the sides of

45 the superstructure 6, wings 9 are connected by hinges 10 for swinging movements in a horizontal plane. These wings 9 contain open compartments or pockets 11, and on their inner edges they are preferably formed 50 on curved lines, so that when turned outward, as shown in Figs. 1 and 2, there will be clearance for the elbows of a person using the flat exposed front portion of the base 5

as a writing or working table. When the wings 9 are folded, as shown in Fig. 3, they 55 form, with the superstructure 6 a rectangular structure that is closed at all sides. To cover up the closed wings, the flat top of the superstructure 6 is formed with a hinged cover plate 12. When the wings are turned 60 outward or unfolded, as shown in Figs. 1 and 2, the cover plate 12 will be turned over on top of the superstructure 6 where it will be entirely out of the way.

Preferably, the abutting edges of the 65 wings 9 are formed with overlapping rabbits 9^a and also, preferably, the lower edges of the rectangular sides of the wings, at their lower edges, are formed with rabbits 9^b that engage a corresponding rabbeted 70 edge 5^a of the base 5. The cover plate 12 may be provided with a shoulder or cleat 75 13, which overlap the rectangular upper edges of the wings and prevent the same from being moved from closed to open positions while the said cover plate is turned downward to operative position, as shown in Fig. 3. It is, of course, obvious, however, that a suitable lock may be applied to positively secure the wings and cover plate in 80 closed positions.

One purpose of the curving or cutting away the wings on their inner sides has already been noted, but it may be further stated that by this formation, when the 85 wings are closed, there is afforded a considerable space within the closed cabinet for containing books, or other articles.

The cabinet described will preferably be made of wood and when nicely finished, will 90 have a very neat and attractive appearance. It is a complete desk and table in itself, and as it is portable and capable of being easily moved from place to place, it may be readily used in connection with any suitable support and, when out of use, it may be easily placed out of the way. Moreover, it may be made at comparatively small cost.

What I claim is:

A desk table of the character described, 100 comprising a base plate, a superstructure covering a portion only of said base and containing compartments, and having a hinged cover plate which, when turned into a horizontal position, extends over the un- 105 covered portion of said base, and wings

hinged to the front portion of the sides of said superstructure and movable from closed positions over the uncovered portion of said base and under the downclosed cover plate 5 into out-turned positions, projecting beyond the sides of the uncovered portion of said base.

In testimony whereof I affix my signature in presence of two witnesses.

FRIDOLIN SCHIMMEL.
